ANTENNA BALUN

Oliver Watson Greene, Box 423, Wakefield, R.I. 02880

Filed Mar. 18, 1969, Ser. No. 16,312

Term of patent 7 years

Int. Cl. D14—99

U.S. Cl. D26—14

FIG. 1

FIG. 2

FIG. 3

FIG. 4

FIG. 1 is a side elevational view of my new design for an antenna balun;

FIG. 2 is a top plan view thereof;

FIG. 3 is a bottom plan view thereof; and

FIG. 4 is an end elevation view.

The non-illustrated side of the antenna balun is the same as the illustrated side of FIG. 1.

I claim:

The ornamental design for an antenna balun, substantially as shown and described.
